(57) **CLAIM**

We claim the ornamental design for a handle for cooking utensil, as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom plan view of a handle for cooking utensil of the claimed design;

FIG. 2 is a top plan view of the handle for cooking utensil shown in FIG. 1;

FIG. 3 is a perspective view of the handle for cooking utensil shown in FIG. 1;

FIG. 4 is a front elevational view of the handle for cooking utensil shown in FIG. 1;

FIG. 5 is a right side elevational view of the handle for cooking utensil shown in FIG. 1; and,

FIG. 6 is a left side elevational view of the handle for cooking utensil shown in FIG. 1.

The ornamental design which is claimed is shown in shaded black in the drawings. The portions of the drawings that are grayed out are for illustrative purposes only and form no part of the claimed design.

1 Claim, 6 Drawing Sheets
